IDA WHALEY STRAHAN, OF MONTCLAIR, NEW JERSEY

CLOTHES SCRUBBING DEVICE

Application filed May 23, 1930. Serial No. 456,769.

My invention is a clothes scrubbing device for use with the usual wash board and an object of the same is to provide a device of this character which may be manipulated with one hand, so that the muscular strain is reduced to a minimum and at the same time will efficiently remove the dirt from the clothes.

A further object of the invention is to provide a clothes scrubbing device embodying a body which is adapted to be rigidly held by the operator and shaped to conform to the corrugations of the wash board so as to cooperate with the latter in washing the clothes as the body is rubbed over the board.

Still another object of the invention is to provide a device of this character which will eliminate rubbing of the human hand on the wash board, will float upon the water and can be manufactured from a single length of wood or other suitable material.

With the preceding and other objects and advantages in mind, the invention consists in the novel combination of elements, constructions and arrangements of parts and operations to be hereinafter more fully described, claimed and illustrated in the accompanying drawing, wherein:

Figure 1 is a perspective of the invention in use;

Fig. 2 is an elevation of the device in use, the wash board and a handkerchief being shown in section;

Fig. 3 is a fragmentary vertical section taken on line 3—3 of Fig. 1.

Referring to the invention in detail an elongated body 5 of suitable length is provided.

One side of the body is shaped to provide a longitudinally extending rounded head 10 which is adapted to be rubbed over the corrugated surface of a wash board as shown.

The opposite side of the body is formed with a longitudinally extending rounded portion 15 adapted to be grasped by the human hand. In order to facilitate grasping of the part 15 the opposite faces of the body 5 are formed with longitudinally extending concavities 16.

In use the device is held at right angles

to the wash with the head 10 in contact with the article to be washed as illustrated particularly in Fig. 1. With the device held in this position it is moved back and forth over the corrugations of the wash board and contacts with the latter in scrubbing the article of clothing. While the device is herein illustrated as being employed to scrub handkerchiefs it may be equally as well employed to scrub other fabrics.

What is claimed is:

A scrubbing device adapted to be used with a washboard comprising a body having an elongated rounded scrubbing head, and an elongated rounded hand grip, the opposite sides of said device intermediate the hand grip and head having longitudinally extending concavities to accommodate portions of the hand when rubbing the device against a wash board.
